**PORTRABLE OUTGOING TRUNK EXTENDER
APPARATUS FOR TELEPHONE OFFICE
EQUIPMENT**

Paul V. De Luca, Port Washington, N.Y., assignor to
Porta Systems Corp., Roslyn, N.Y.

Filed Jan. 20, 1972, Ser. No. 219,611

Term of patent 14 years

Int. Cl. D14—03

U.S. Cl. D26—14 A

FIG. 1

FIG.2

FIG.3

FIG.4

FIG. 1 is a perspective view of a portable outgoing trunk extender apparatus for telephone office equipment embodying my new design;

FIG. 2 is a top plan view of the portable outgoing trunk extender apparatus of FIG. 1;

FIG. 3 is a rear view of the portable outgoing trunk extender apparatus depicted in FIG. 1; and

FIG. 4 is a side view of the portable outgoing trunk extender apparatus shown in FIG. 1.

I claim:

The ornamental design for a portable outgoing trunk extender apparatus for telephone office equipment, substantially as shown.
